(57) **CLAIM**

The ornamental design for a shoe sole, as shown and described.

DESCRIPTION

FIG. 1 is a perspective view of applicant's shoe sole design; FIG. 2 is a front view of the shoe sole of FIG. 1;

FIG. 3 is a rear view of the shoe sole of FIG. 1;

FIG. 4 is a left side view of the shoe sole of FIG. 1;

FIG. 5 is a right side view of the shoe sole of FIG. 1;

FIG. 6 is a plan view of applicant's shoe sole design; and,

FIG. 7 is a bottom view of the shoe sole.

The broken lines in the figures are for purposes of illustrating portions of the shoe sole that form no part of the claimed design.
